CLAIM

The ornamental design for a spacer for separating a rubber seal from a vehicle window glass to be used by traffic constables, as shown and described.

DESCRIPTION

FIG. 1 is a perspective view of a spacer for separating a rubber seal from a vehicle window glass to be used by traffic constables showing my new design;

FIG. 2 is a top plan view thereof;

FIG. 3 is a front elevational view thereof with the adjacent and opposite sides being identical in appearance; and,

FIG. 4 is a bottom plan view thereof.
